TRACTION MAINTAINING TURNING FRAME

Clifford W. Hogan, Minneapolis, Minn.

Application May 25, 1951, Serial No. 228,268

4 Claims. (Cl. 128—84)

1

This invention relates generally to turning frame assemblies for hospital use and the like and particularly to a turning frame designed to facilitate maintaining constant traction on a patient lying therein, even while the frame is being turned.

In conventional types of turning frames, it is difficult, if not impossible, to maintain a constant traction on a patient by the use of a pulley and weight system, while the patient is being turned, and during this period the pulley and weight system must be removed to prevent possible injury to the patient.

It is an object of my invention to provide an improved turning frame designed to permit a pulley and weight traction system to be maintained even while a patient held in the turning frame is being turned.

More specifically, it is an object to provide a turning frame having provision for permitting the flexible cord element of a pulley and weight traction system to be aligned with the axis of turning to permit the frame to be turned about its axis without causing any variation in the tension in the cord.

Still more specifically, it is an object to provide a turning frame provided with a supporting structure having a pair of hollow trunnions respectively journaled in the end portions thereof to permit the flexible cord of a pulley and weight traction system to be threaded therethrough to lie substantially coincident with the axis of turning and thereby permit the frame to be turned about said trunnions without varying the tension in the cord and without causing any shifting movement of the cord during the turning operation, the frame mounted on said trunnions having guiding means to permit straight line pull to be exerted by the cord on the patient and to guide the cord to the inner end of the hollow trunnion to permit the same to extend therethrough without excessive friction being applied to the cord.

These and other objects and advantages will more fully appear from the following description made in connection with the accompanying drawings wherein like reference characters refer to the same or similar parts throughout the several views and in which:

Fig. 1 is a perspective view of a complete turning frame embodying my invention;

Fig. 2 is a fragmentary end elevational view of one end of my turning frame;

Fig. 3 is a bottom plan view of the structure shown in Fig. 2 and with portions thereof broken away; and

Fig. 4 is a side elevational view of one end of my frame with portions thereof cut away.

As illustrated in the accompanying drawings, I provide a turning frame adapted to be mounted on a conventional supporting structure, which, in the form shown, consists in a wheeled base 8 having the longitudinally disposed spaced parallel leg carrying angles 9. The angles 9 are adapted

2

to receive the longitudinal portion of the divergent legs 10, which, in the form shown, comprise a pair of elongated tubular members respectively bent to form a relatively rigid pair of supporting legs which have their upper ends respectively fixed to a pair of longitudinally spaced stationary interconnection members 11 and combine therewith to form a supporting cradle for the turning frame. An overhead frame 12 is rigidly fixed to said interconnection member 11, as by being set screwed thereto.

An aperture is formed in the central portion of each of the interconnection members 11 and a pair of hollow trunnions 13 are respectively journaled therein. A pair of turning frame mounting members or hubs 14 are fixed to the respective trunnions 13 and a pair of externally threaded frame mounting spindles 15 and 16 are fixed in oppositely extending relation to each of 20 said mounting members. Conventional upper and lower patient supporting frames 17a and 17b are shown respectively mounted on the two pairs of spindles 15 and 16, and are securely retained thereon by the thumb screws 15a and 16a respectively.

Suitable guiding means for guiding a traction applying flexible cord 18 are provided for one or both ends of the turning frame such as the sheaves 19 and 20 mounted on mounting member 30 14. The lower sheave 19 is mounted on a swingable arm 21 which may be swung upwardly or downwardly to vertically position the sheave 19, and permit the desired line of pull to be maintained on the patient lying in the frame. The 35 sheave 20 is also mounted on a swingable arm 22 to guide the line 18 through the center of the hollow trunnion 13. Both arms 21 and 22 may be secured in their adjusted position by such means as threaded clamps 21a for clamping arm 21 at 40 its pivot and 22a for clamping arm 22 at its pivot on the mounting member 14. As will be seen from inspection of Fig. 4 the arm 22 is adjustable for axially positioning cable 18 through the bore of trunnion 13 and arm 21 is adjustable for applying traction longitudinally of a patient's body at a preselected radial distance with respect to the axis of the bore. The trunnions 13 are retained in the interconnection members 11 by locking collars 23 respectively secured thereto as by any suitable means such as set screws. Outer guiding means are also provided, such as the sheave 24 journaled on suitable supporting arms 25 which are fixed to each of the interconnection members 11 and extend outwardly therefrom. This outer 50 guiding sheave 24 permits the weights attached to line 18 to hang free and exert a constant pull thereon. Any conventional means for normally holding the hubs 14 in fixed relation to the respective interconnection members 11 may be provided such as the spring pressed pins 26 slidably mounted in the respective interconnection members and normally urged by suitable springs toward the respective hubs 14 which are provided

with suitably positioned apertures to respectively receive the pins 26 and lock the hubs 14 against rotation. Obviously, the pins 26 may be retracted at each end of the frames 17a and 17b when it is desired to turn the patient over.

With my improved turning frame, a weight and pulley traction system may be constantly maintained on a patient in predetermined tensioned relation to the patient even while the patient is being turned over for temporary examination or treatment. Since the pulleys or sheaves 19 and 20 always remain in predetermined relation to the patient who is securely fixed to the frames 17a and 17b, there is no variation in the length of the cord and no shifting of the cord during the turning operation. The outer guiding sheave 24 remains in fixed position at all times and the portion of the cord 18 extending between sheaves 20 and 24 lies in the axis of turning of the frames 17a and 17b and thereby prevents any shifting of the cord during the turning operation.

Doctors have used turning frames for a number of years but have always had the problem of not being able to constantly maintain the desired traction on the patient held therein. The cord 18 is, of course, fastened to the patient in any conventional manner to apply the desired traction and my improved device permits this traction to be constantly maintained.

It will be seen that I have provided an extremely ingenious yet relatively simple turning frame construction which is designed to position a portion of a traction applying cord in substantial alignment with the axis of turning to permit a weight and pulley traction system to be used and permit the traction applied thereby to be maintained substantially constant even during the turning operation. Suitable cord guiding means are provided to reduce the frictional resistance to ultimate positioning of the weight and thus aid in maintaining a substantially constant adjusted tension therein.

It will of course be understood that various changes may be made in the form, details, arrangements, and proportions of the parts without departing from the scope of my invention.

What I claim is:

1. An invalid bed for turning a patient while maintaining a portion of the patient's body under traction comprising a supporting frame, a turning frame disposed for holding and turning the body of said patient about a longitudinal axis across opposed portions of the supporting frame, cooperating trunnioned elements between said supporting frame and said turning frame at the opposed junctures thereof, each of said cooperating trunnioned elements comprising an interconnection member fixed to the supporting frame and a mounting member fixed to said turning frame, both of said members in at least one of said cooperating trunnioned elements having an opening in axial alignment with said longitudinal axis for guided travel of a traction cable therethrough, and guide means on said mounting member offset radially from said axis whereby a weighted traction cable may extend in guided relation through said opening and connect with the body of said patient at a preselected traction point irrespective of the angular inclination of the patient's body.

2. An invalid bed for turning a patient while maintaining a portion of the patient's body under traction comprising a supporting frame, a turning frame disposed for holding and turning the body of said patient about a longitudinal axis

across opposed portions of the supporting frame, cooperating trunnioned elements between said supporting frame and said turning frame at the opposed junctures thereof, each of said cooperating trunnioned elements comprising an interconnection member fixed to the supporting frame and a mounting member fixed to said turning frame, both of said members in at least one of said cooperating trunnioned elements having an opening in axial alignment with said longitudinal axis and defining a passageway therethrough, outer guide means secured to said interconnection member adjacent said axis, and movable guide means secured to said mounting member and rotatable therewith, whereby a weighted traction cable may extend in guided relation through said opening and connect with the body of said patient at a preselected traction point irrespective of the angular inclination of the patient's body.

3. An invalid bed for turning a patient while maintaining a portion of the patient's body under traction comprising a supporting frame, a turning frame disposed for holding and turning the body of said patient about a longitudinal axis across opposed portions of the supporting frame, cooperating trunnioned elements between said supporting frame and said turning frame at the opposed junctures thereof, each of said cooperating trunnioned elements comprising an interconnection member fixed to the supporting frame and a mounting member fixed to said turning frame, both of said members in at least one of said cooperating trunnioned elements having an opening in axial alignment with said longitudinal axis and defining a passageway therethrough, fixedly mounted guide means secured to said interconnection member and extending outwardly therefrom adjacent said axis and movable guide means secured to said mounting member and rotatable therewith about said axis, whereby a weighted traction cable may extend in guided relation through said opening and connect with the body of said patient at a preselected traction point irrespective of the angular inclination of the patient's body.

4. In a bed for turning the body of a patient while maintaining a portion thereof under constant traction comprising a supporting frame, a turning frame trunnioned for longitudinal oscillation across said supporting frame, the trunnioned portion having an axial opening disposed therethrough in at least one of said trunnions, guide elements for guiding a weighted traction cable axially of said opening, and an offset guide member adjustable radially with respect to the axis of said opening and mounted for rotation on said supporting frame whereby the portion of the patient's body under traction will be maintained under directional traction at a preselected tension irrespective of the angular inclination of the patient's body.
